US00D754444S

(12) United States Design Patent
Williams

(10) Patent No.: US D754,444 S
(45) Date of Patent: * Apr. 26, 2016

(54) FABRIC OR THE LIKE WITH CAMOUFLAGE PATTERN

(71) Applicant: Aaron Joel Williams, Fallon, NV (US)

(72) Inventor: Aaron Joel Williams, Fallon, NV (US)

() Term: 14 Years

(21) Appl. No.: 29/497,745

(22) Filed: Jul. 28, 2014

(51) LOC (10) Cl. 05-02

(52) U.S. Cl.

USPC D5/60

(58) Field of Classification Search

USPC ..... D5/1-5, 7, 8, 11, 12, 13, 14, 17, 19, 20, D5/23, 25, 26, 28, 32, 35, 37, 39, 43, 45, D5/46, 47, 50-53, 55-59, 60-65, 99; D6/304, 578, 583-585, 587, 589, 596, D6/598, 602, 603, 608, 609, 613, 614, 616, D6/617, 621, 622; D19/1, 5; D25/138, D25/142, 149, 151, 152; D2/502, 508 CPC B31F 1/07; B32B 3/266; B32B 5/024; B44F 1/00; B44F 1/02; B44F 1/08; B44F 1/10; B44F 3/00; B44F 5/00; B44F 7/00; B44F 9/00; B44F 9/04; D03D 1/00; D03D 25/00; D04H 1/00; D10B 2503/00; D10B 2503/04; D21H 27/02

(57) CLAIM

The ornamental design for a fabric or the like with camouflage pattern, as shown and described.

DESCRIPTION

The sole FIGURE is a top plan view illustrating my design for a fabric or the like with camouflage pattern. The broken lines depict the boundary of the claimed design and form no part of the claimed design.

1 Claim, 1 Drawing Sheet
